BOTTLE CROWN CAP ASSEMBLING
MACHINE GLUING ATTACHMENT

Berthold Nagy, Brooklyn, N. Y.

Application March 6, 1951, Serial No. 214,074

4 Claims. (Cl. 118—255)

1

This invention relates to bottle crown assembling machines wherein cork liners are installed in bottle crown caps, and in particular an improved gluing attachment for depositing a thin film of glue on the inner surfaces of crowns before the cork discs or liners are deposited therein.

The purpose of this invention is to provide an improved gluing attachment for bottle crown assembling machines in which only a thin film of glue is deposited in the caps and in which the thickness of the film may be regulated.

This invention is an improvement over the gluing and adhesive feeding instrumentalities of my prior Patent No. 2,069,897 for Bottle Closure Assembling Machines, over the Adhesive Feeder of my Patent No. 2,062,900, and the Bottle Crown Adhesive Feeding Device of my Patent No. 2,066,071, and this invention is a modification of the Bottle Crown Paraffin Coating Device of my patent No. 2,229,116, in that the glue carrying wheel that applies glue to the daubers which deposit the glue in the crowns and also all other associated parts that come in contact with the glue are removable from the machine whereby they may be removed and placed in water during periods when the machine is inoperative to prevent glue hardening thereon.

A further improvement in the attachment of this invention is in the position of the glue storage container, as the glue carrying wheel that applies glue to the daubers that deposit the glue in the crowns is removed from the container or pot of glue and the glue is fed to the wheel in comparatively small quantities.

The object of this invention is, therefore, to provide a glue applying attachment for bottle crown cap assembling machines in which the peripheral surface, only, of a wheel that applies glue to daubers that deposit the glue in the crown contacts the glue and in which the thickness of the film of glue that adheres to the surface of the wheel is regulated.

Another object of the invention is to provide means for mounting the improved glue applying attachment on a bottle crown cap assembling machine without materially changing the structure of the machine.

Another object of the invention is to provide an improved glue applying attachment for bottle crown cap assembling machines in which means is provided for adjusting the amount of glue fed to a receptacle into which the glue carrying wheel that applies the glue to the daubers which place the glue in the crowns, extends.

Another object of the invention is to provide

2

means for forming the parts of a glue applying attachment of bottle crown cap assembling machines wherein the parts are readily removed and replaced.

A further object of this invention is to provide means for actuating a glue carrying wheel and a dauber carrying hub of a bottle crown cap assembling machine whereby the surface speed of the daubers is greater than that of the glue carrying wheel so that the contacting area of one dauber on the surface of the wheel substantially engages the trailing edge of the contacting area of the preceding dauber and substantially all glue is continuously removed from the surface of the wheel.

A still further object of the invention is to provide an improved gluing attachment for bottle crown cap assembling machines that wipes substantially all glue from the surface of a glue carrying wheel and in which the parts are readily removable from the machine, which is of a comparatively simple and economical construction.

With these and other objects and advantages in view the invention embodies a stand for mounting the parts of the attachment on a bottle crown cap assembling machine, a hub journaled on the stand and having daubers extended therefrom for applying glue to the inner surfaces of crown caps, a glue carrying wheel for applying glue to the daubers, means driving the glue carrying wheel from the dauber carrying hub whereby the meeting areas of contact of the daubers with the surface of the wheel substantially cover the surface of the wheel, glue feeding means wherein the amount of glue supplied to the glue carrying wheel is limited, and means removably mounting the parts on the stand so that the parts may be separated and placed in water after use.

Other features and advantages of the invention will appear from the following description taken in connection with the drawings, wherein:

Figure 1 is a plan view showing an outline of a bottle crown cap assembling machine with the improved gluing attachment thereon.

Figure 2 is a plan view showing a slight change required in the rail ring guide cover in order to accommodate the daubers of the improved gluing attachment of this invention.

Figure 3 is a longitudinal sectional view through the dauber carrying hub of this invention.

Figure 4 is an end elevational view of a collar mounted on the driving mitre gear shaft of the stand on which the attachment is mounted, and showing the location of a pin extended from the

collar for positioning the dauber carrying hub in relation to the crown sprocket of the machine.

Figure 5 is an end elevational view of the stand by which the attachment is mounted on the crown cap assembling machine.

Figure 6 is a sectional view through the attachment, taken on line 6—6 of Figure 5; illustrating the relative positions of the dauber hub and glue carrying wheel.

Figure 7 is a longitudinal sectional view through the dauber hub taken in line 7—7 of Figure 6 showing the mounting elements thereof, and illustrated with some of the parts shown in elevation.

Figure 8 is a similar sectional view through the glue carrying wheel, taken on line 8—8 of Figure 6, and also showing the shaft and bearings for mounting the wheel in the glue receptacle.

Figure 9 is a plan view of the improved gluing attachment with parts broken away.

Figure 10 is a front elevational view of the attachment with parts broken away taken on line 10—10 of Figure 9.

Figure 11 is a plan view showing the glue receptacle.

Figure 12 is a cross section through the glue receptacle taken on line 12—12 of Figure 11, with parts omitted and with parts shown in elevation.

Referring now to the drawings wherein like reference characters denote corresponding parts the improved gluing attachment for rotary bottle crown cap assembling machines of this invention includes a dauber hub 10 mounted on a stand 11 that is positioned on the rail ring cover 113 of a bottle cap assembling machine, a glue carrying wheel 12 rotatably mounted in a glue receptacle 13, which is mounted on the stand through a bracket 14, a glue storage container 15, and suitable driving and operating instrumentalities.

The dauber hub 10 is formed as shown in Figures 3 and 7, and the hub, which is actuated through mitre gears 16 and 17, is provided with a sleeve 18 having a bore 19 therethrough. The sleeve is mounted on a stud 20 on the outer end of which a gear 21 is positioned, and the stud is provided with a wing nut-like head by which it may readily be turned by hand. The end of the stud is provided with left hand threads with which it is threaded into a socket 22 in a collar 24 on the outer surface of the mitre gear 17 and integral therewith, and the face of the hub 10 is provided with a circular recess 23 which receives the end of the collar, as shown in Figure 7. The collar 24 is also provided with a positioning pin 25 that extends into an opening 26 in the dauber hub 10 which provides means for locating the rubber dauber pads so that they register with the crown caps in the crown sprocket.

The daubers are formed with round rubber pads 27 which have small openings 28 therein and these pads are spaced to register with crown caps in the crown sprocket disc 29, as shown in Figure 6.

The dauber pads 27 are mounted in cups 30 on the outer ends of stems 31, and the stems, which are provided with flat sections 32, are positioned in radially disposed openings 33 in a rim 34 of the dauber hub 10. The stems are secured in the rim by set screws 35 which are threaded in the rim, and positioned to contact the flat surfaces of the stems of the dauber pads. By this means the daubers are accurately positioned so that they will engage the inner surfaces of the crown caps with any pressure desired.

The stand 11, on which the dauber hub is

mounted, is provided with a bearing 36 at the upper end of which a shaft 37, on which the gear 17 is mounted is journaled. The mitre gear 16 that meshes with the gear 17 is mounted on a spindle 38 also journaled in the stand 11, and on the lower end of the spindle is a gear 39 that meshes with the crown sprocket gear 40, as shown in Figure 5, and which provides means for driving the gluing attachment.

The gear 21 on the outer end of the stud 20 drives a gear 41 on a shaft 42 through pinions 43 and 44 on an arm 45 which is pivotally mounted in a casing 46 by a pin 47 and the arm is resiliently held by a spring 48 so that the gears are retained in operative engagement as the position of the glue carrying wheel 12 is adjusted in relation to the dauber hub 10. The shaft 42 is journaled in bearings or sockets 49 and 50 in the upper ends of posts 51 and 52 in the sides of the receptacle 13, and the end of the shaft 42 in the bearing 49 is secured in position by a spring clip 53.

The gear housing or casing 46, which provides a guard or cover for the gears 21 and 41, is carried by the stud 20 and shaft 42 with a wall 96 of the housing provided with an opening 196 in which the hub of the gear 21 is journaled, and a similar opening 199 is provided in the cover plate 99 in which the opposite end of the hub of the gear is journaled. At the opposite end of the housing, the shaft 42 extends through the slot 97 in the wall 96 and also through the slot 98 in the cover plate. By this means the housing remains stationary with the gears turning therein, and the distance between the gears is adjustable.

The receptacle 13 is formed with an arcuate inner end 54 that fits snugly around the wheel 12 and a triangular-shape outer end 55, and the intermediate part is provided with an elongated hub 56 which extends from one side, and through which a glue passage 57 is provided that opens into the receptacle at a point below the glue carrying wheel 12. The upper side of the outer end of the hub 56 is provided with a collar 58 which has vertically disposed ribs 59 on the outer surface, and a cap 60, threaded on a neck 61 of the glue container 15 fits snugly over the ribs with the container in the inverted position, as shown in Figure 12, wherein glue is being fed to the receptacle 13 as it is used therefrom. The side walls of the outer end of the hub 56 are provided with brackets 62 and 63 in which adjusting screws 64 and 65 are clamped by screws 66 and 67. The screws 64 and 65 engage the lower end of the glue container cap and thereby provide means for adjusting the position of the container to regulate the amount of glue in the passage 57, and consequently in the receptacle.

A cleaning plug 68 having a finger gripping tab 69 on the outer end is threaded in the outer end of the hub 56 to provide means for brushing out the accumulated glue in the passage 57.

The cap 60 is provided with a throat 70 having a conical shape inner surface 71 which forms a valve seat for a valve 72 on the upper end of a stem 73, and the lower end of the stem is provided with a ball 74 which, with the parts in the position shown in Figure 12, rests upon the inner surface of the hub 56 and supports the valve 72 in an upper position in which the valve is open so that glue is free to pass therethrough. When the glue container 15 is removed the ball drops downwardly and draws the valve into the seat thereby closing the lower end of the container and preventing glue spilling therefrom. With the position of the container 15 adjusted to

supply glue at the desired level in the receptacle 13, the screws 64 and 65 are secured by the screws 66 and 67.

The elevation of the glue in the receptacle 13 is adjusted whereby the peripheral surface of the wheel 12 is immersed in the glue and the amount of glue remaining on the wheel is governed by a scraper 76 having a scraping edge 77 that is positioned between fingers 78 and 79. The scraper 76 extends from the inner leg of a U-shaped spring clip positioned over the end wall of the outer end 55 of the receptacle and the clip is secured in position by screws 80, as shown in Figures 6 and 11. The position of the scraping edge is adjusted by a thumb screw 81 which is threaded in a boss 82 on the outer surface of the end wall of the receptacle, and the thumb screw is secured in adjusted positions by a lock nut 83. By this means all excess glue is removed from the surface of the wheel 12 so that only the desired amount is deposited in the crown caps.

The glue receptacle 13 is provided with a threaded stud 84 that extends from a lug 85, and the stud, which extends through a flange 86 on the bracket 14, is held by a nut 87, as shown in Figure 6.

The bracket 14 is adjustably mounted on a base plate 88 of the stand 11 with bolts 89 and 90 in a flange 91 on the lower end of the bracket. The bolts extend through elongated slots 92 and 93 in the base plate, and in order to hold the bracket in alignment a key 94 on the under side of the flange extends into a slot 95 in the base plate. By this means the position of the surface of the wheel 12 is adjusted in relation to the surfaces of the dauber pads 27, thereby providing additional means for regulating the amount of glue wiped from the surface of the wheel 12 by the rubber daubers.

In order to adjust the distance between the shaft 42 and the stud 20, the inner wall 96 of the gear casing 46 is provided with an elongated opening 97, as shown in dotted lines in Figure 6, and a similar opening 98 is provided in a cover plate 99, that is secured in the open side of the casing by screws 100. The wall 96 is also provided with a recess 101 in which the arm 45 is positioned and one end of the spring 48 is mounted on a pin 102 which extends from the arm 45 through a slot 103 in the wall 96. The opposite end of the spring is held on a stud 104 that extends from the outer surface of the wall 96, and with the parts mounted in this manner the spring holds the pinion 44, which is journaled on the arm 45 by a pin 105, in meshing engagement with the gear 41. By this means the gears provide operating means between the dauber hub and glue carrying wheel without changing the gear ratio.

The shaft 42 which is journaled, or freely mounted in the open bearings or sockets 49 and 50 is provided with a collar 106 that is positioned against the outer surface of the bearing 50, and the gear casing 46 is clamped against the outer surface of the collar by a thumb nut 107. The thumb nut 107 and outer end of the shaft are provided with left hand threads to prevent the nut turning back or loosening on the shaft. The opposite end of the shaft is held in an opening 108 in the spring clip 53, and the clip 53, which is provided with thumb receiving recesses 109, in the sides, is mounted on a screw 110 that is threaded into the post 51, and a

spring 111 on the screw holds the clip in the position, as illustrated in Figure 8, whereby the shaft is retained in the bearings and when it is desired to remove and replace the shaft the clip is drawn outwardly by hand, against the spring, until it passes beyond the end of the shaft.

The attachment is provided with safety or protecting cover plates, such as the plates 112, shown in Figure 5, which cover the gears 16 and 17, and similar cover plates are provided for the gears 39 and 40, and other parts of the attachment.

The rail ring cover 113 of the machine, as shown in Figure 2, which is provided with an elongated slot 114, is formed with a straight section 115 on the inner side of the slot, and notches 116 and 117 are provided in the outer edge of the ring guide cover to provide clearance for the rubber daubers 27 and the dauber holding cups 30.

With the parts arranged in this manner the stud 20 and the nut 107 are removed when it is desired to discontinue operation of the machine, and the gear housing, dauber hub 10, and glue carrying wheel 12, are taken from the attachment or machine and placed in water over night, or until it is desired to again start the machine. By this means glue does not harden on the parts of the attachment, and the entire attachment may be thoroughly cleaned.

With the gears for driving the glue carrying wheel from the dauber hub arranged as shown in Figure 10, the speed of the wheel 12, being less than that of the hub 10, causes the rubber daubers 27 to wipe over the surface of the wheel with a sliding action, and with the speed ratio proportioned accordingly one pad follows another, as illustrated by the dotted lines in Figure 6, whereby the leading edge of one dauber meets the trailing edge of the area on the surface of the wheel where the dauber ahead has contacted and wiped the wheel, so that substantially the entire surface of the wheel is engaged by the dauber pads.

In positioning the attachment parts on the stand it is only necessary to place the dauber hub 10 against the face of the collar 24 with the end of the collar in the recess 23 and with the opening 26 positioned over the pin 25 of the collar, and with the gear 21 in the housing 46 positioned on the stud 20, the threaded end of the stud is placed through the sleeve 18 and threaded with the left hand threads into the socket 22 of the collar 24. These parts are assembled with the gear 41 on the shaft 42, and with the shaft 42 in position in the open bearings 49 and 50 of the glue receptacle 13, and after the parts are in position the nut 107, which is also provided with left hand threads, is placed on the extended end of the shaft 42.

It will be noted, therefore, that with the gear 41 on the shaft 42 and with the shaft 42 positioned in the bearings of the receptacle 13 the stud 20, with the gear 21 thereon is inserted through the dauber hub and threaded into the socket 22 of the collar 24, and with these parts in position the wheel 12 is adjusted in relation to the daubers by sliding the bracket 14 in the slots 92 and 93 of the base of the stand. In this movement the pinions 43 and 44 swing the arm 45 about the pivot 47 so that the positions of the parts may be adjusted without changing the gear ratio.

These gears and also the glue receptacle and

container are readily removable from the attachment.

It will be understood that modifications may be made in the design and arrangement of the parts without departing from the spirit of the invention.

Having thus fully described the invention what I claim and desire to secure by Letters Patent, is:

1. A gluing attachment for bottle crown cap assembling machines comprising a stand, a horizontally disposed shaft journaled in said stand, a dauber hub removably mounted on one end of the said shaft, a plurality of spaced radially disposed daubers extended from said dauber hub, a glue receptacle mounted on said stand, a glue carrying wheel journaled in said receptacle and positioned whereby the peripheral surface thereof is in contact with a dauber of the said dauber hub, and transmission means for rotating the said glue carrying wheel from the dauber hub whereby the surface speed of the wheel is less than the traveling speed of the daubers so that as one dauber leaves the surface of the wheel a following dauber contacts the surface of the wheel with the leading edge thereof substantially engaging the trailing edge of the area on the surface of the wheel contacted by the preceding dauber.

2. A gluing attachment for bottle crown cap assembling machines comprising a stand, a vertically disposed shaft journaled in the said stand, gears on the upper and lower ends of the shaft, a horizontally disposed shaft journaled in the upper part of the stand, a gear on the horizontally disposed shaft positioned to mesh with the gear on the upper end of the vertically disposed shaft, a collar having a pin extended therefrom and having a socket with left hand threads therein carried by and integral with the gear on the horizontally disposed shaft, a dauber hub having a rim concentric with the axis of the hub and having spaced radially disposed glue applying pads extended from the rim thereof positioned against the face of the said collar and having an opening therein positioned to receive the said pin extended from the said collar, a stud extended through the dauber hub and threaded into the said socket for securing the dauber hub on the collar, a glue receptacle mounted on the stand, means feeding glue to the said receptacle, a glue carrying wheel journaled in the said receptacle and positioned whereby the peripheral surface thereof engages the pads of the daubers, and transmission means for rotating the said glue carrying wheel by the stud on which the dauber hub is mounted whereby the surface speed of the wheel is less than the traveling speed of the daubers so that as one pad leaves the surface of the wheel a following pad contacts the surface of the wheel with the leading edge thereof substantially engaging the trailing edge of the area on the surface of the wheel contacted by the preceding dauber.

3. In a gluing attachment for bottle crown cap assembling machines, the combination which comprises a stand adapted to be mounted on a bottle crown cap assembling machine, a vertically disposed shaft journaled in the stand and having a gear on the lower end thereof positioned to mesh with the crown sprocket gear of the machine, a horizontally disposed shaft having a collar with a pin eccentrically positioned on the outer face journaled in the upper part of the stand, said collar having a socket in the center

thereof and said socket having left hand threads therein, means driving the horizontally disposed shaft from the vertically disposed shaft, a dauber hub positioned against the face of the collar and having a positioning opening therein for receiving the pin extended from the collar, radially disposed daubers extended from said dauber hub, a stud having a gear thereon extended through the dauber hub and threaded with left hand threads into the said collar, a glue receptacle having open bearings in side walls thereof adjustably mounted on the stand, a shaft having a gear secured thereon with a nut having left hand threads journaled in the said open bearings of the receptacle, a glue carrying wheel mounted on the shaft in the glue receptacle and positioned whereby the surface thereof is in contact with faces of the daubers of the dauber hub, and adjustably mounted and constantly meshing gears positioned between and meshing with the gears of the dauber hub and glue carrying wheel whereby the distance between the wheel and faces of the daubers is adjustable, the gear ratio between the gears of the glue carrying wheel and dauber hub being such that the glue carrying wheel is rotated with the surface speed thereof less than the speed at which the daubers travel and whereby the contacting areas of the daubers on the surface of the wheel are in meeting relation.

4. In a gluing attachment for bottle crown cap assembling machines, the combination which comprises a stand, a horizontally disposed shaft having a collar with a pin extended therefrom on one end journaled in said stand, a dauber hub positioned against the face of the said collar and having a positioning opening therein for receiving the said pin extended from the collar, radially disposed daubers extended from said dauber hub, a stud having a gear thereon extended through the dauber hub and threaded into the said collar, a glue receptacle mounted on the said stand, a glue carrying wheel mounted in the said receptacle and positioned to contact the faces of the daubers of the dauber hub, a shaft having a gear thereon journaled in the said receptacle and on which the said glue carrying wheel is mounted, a gear housing extended around the gears of the said dauber hub stub and glue carrying wheel shaft, an arm pivotally mounted in said gear housing, meshing pinions journaled on the said arm and positioned with one of said pinions meshing with the gear of the dauber hub stub and the other with the gear of the glue carrying wheel shaft thereby providing means for retaining the gears in meshing relation with the distance between the dauber hub and glue carrying wheel adjustable and without changing the speed ratio between the dauber hub and glue carrying wheel shaft, and means for adjusting the position of the said receptacle on the stand.

BERTHOLD NAGY.
